Attorney

UNITED STATES PATENT OFFICE.

THOMAS N. PHELAN, OF MADISON, WISCONSIN.

WORK GUIDE AND SUPPORT FOR DRILL-PRESSES.

1,267,447.

Specification of Letters Patent. Patented May 28, 1918.

Application filed October 22, 1917. Serial No. 197,933.

To all whom it may concern:

Be it known that I, THOMAS N. PHELAN, a citizen of the United States, residing at Madison, in the county of Dane and State 5 of Wisconsin, have invented certain new and useful Improvements in Work Guides and Supports for Drill-Presses, of which the following is a specification, reference being had to the accompanying drawings.

10 This invention relates to attachments for drill presses, and particularly to a means for holding work upon a drill press.

The general object of the invention is to provide a very simple and readily adjusted 15 work guide and support, whereby work may be disposed in place upon the small drill presses and properly disposed beneath the drill, without the necessity of holding the work beneath the hands, thus leaving the 20 operator to a large extent free to control the press, and further supporting the work so that it may be accurately drilled.

A further object is to provide a device of this character which can be folded into 25 relatively small compass and which has a relatively large range of adjustment, and further to provide a construction of this character so formed that the work engaging member may be inclined to fit against and 30 support a piece of work having an inclined face.

Other objects will appear in the course of the following description.

My invention is illustrated in the accompanying drawings, wherein:-

35 Figure 1 is a plan view showing the application of my device to a drill press bed;

Fig. 2 is a top plan view of my improved clamp;

40 Fig. 3 is an end view thereof; and

Fig. 4 is a like view to Fig. 2, but showing the parts contracted.

Referring to these drawings, 10 designates what I shall term the base member of the 45 holder or guide, this member being formed of a strip of metal about 24" long, under ordinary circumstances, and about $\frac{1}{4}$ " thick and any suitable width. The work engaging member is designated 11 and is prefer- 50 ably made of a strip of 2" angle iron. Piv- oted to the member 11 are links 12 and 13.

The link 13 is pivoted to the base member, but the link 12 is preferably detachably piv- 55 oted to the base member by forming the base member with a plurality of perfora- tions 14, disposed in different positions, the

adjacent extremity of the link 12 being per- 60 forated and the pin 15 being provided which may pass through the perforations in the link 12 and into any one of the perfora- tions 14. This pin 15 is preferably con- 65 nected to the link 12 by means of a short chain, so that the pin cannot be lost. The link 13 carries upon it a locking brace 16, which is pivoted at 17 to the link 13, the 70 lower end of this brace being perforated for the passage of a pin 18. The member 11 is formed with a plurality of perforations 19 arranged in two longitudinally extending 75 series with any one of which perforations 80 the pin 18 may engage.

It will be obvious that the member 10 may be closed against the member 11, so that the members 10 and 11 are in close 85 contiguity, or the members 10 and 11 may be separated to an extent only determined by the length of the links 12 and 13, and that the members 10 and 11 may be held in their adjusted, separated relation by pass- 90 ing the pin 18 through one of the perfora- tions 19 thus bracing the link 13. By ad- justing the pin 15 in the perforations 14, the members 10 and 11 may be given dif- 95 ferent relative angles, so that work which has an inclined face may be readily sup- 85 ported, thus adapting the device to various kinds of work and various situations. It will be obvious that by forcing the links 12 and 13 outward away from the member 11, that a wedging action may be secured, which 90 will cause the work to be very firmly clamped in place against an abutment on the bed plate of the press.

In Fig. 1, I have shown this device ap- 95 plied to the bed plate 20 of an ordinary drill press. In this case the member 10 is supported against bolts 21, which pass through the usual openings on the press bed and the links 12 and 13 are so adjusted as to hold the member 11 in such a position 100 that the work 22 will be supported in proper position beneath the drill. It is obvious that the member 10 may be abutted against a rear flange which is present on some bed plates, or against any other object or por- 105 tion of the press with which it may be engaged.

Having described my invention, what I claim is:

1. A work holder and guide for drill 110 presses comprising a base member and a work engaging member, links pivoted to the

- base member and to the work engaging member, and means holding the links at variable angles with relation to the work engaging and base members.
5. 2. A work holder and guide for drill presses comprising a base member and a work engaging member, links pivoted to the base member and to the work engaging member, and means for holding the links at variable angles with relation to the said members, said means comprising a base pivotally attached to one of said links, the opposite end of the brace being perforated and one of said members being longitudinally perforated, and a pin adapted to be passed through the perforation in the base and through any one of the perforations in the said member with which the base engages.
3. A work holder and guide for drill presses comprising a base member and a work engaging member, a link pivoted to the base member and to the work engaging member, a second link pivoted to one end of the work engaging member and perforated at its other end, the base member being provided with a plurality of perforations, a pin passing through the perforation in the second named link and through any one of said perforations in the base member, and means for holding the links in an angularly adjusted relation to the work engaging mem-
- ber and base member comprising a brace pivotally connected to the first named link and perforated at its opposite extremity, and a pin adapted to pass through said perforations, the work engaging member being formed with a plurality of longitudinally extending perforations with which said pin can be engaged.
4. A work holder and guide for drill presses comprising a base member and a work engaging member, links pivoted to the work engaging member, means for adjustably pivoting one of said links to the base member at any one of a plurality of points, to thereby hold the said members in different angular relations to each other, and means for holding said members spaced apart at variable distances.
5. A work holder and guide for drill presses, comprising a base member and a work engaging member, means for adjusting said members in different spaced relations from each other, and means for adjusting said members into different angular relations to each other.

In testimony whereof I hereunto affix my signature in the presence of two witnesses.

THOMAS N. PHELAN.
